UNITED STATES PATENT OFFICE.

HARRY A. TAYLOR, OF NEW YORK, N. Y.

DESIGN FOR A LADY'S UNDERVEST OR SIMILAR UNDERGARMENT.

48,135.

Specification for Design.

Patented Nov. 9, 1915.

Application filed January 9, 1915. Serial No. 1,467. Term of patent 7 years.

To all whom it may concern:

Be it known that I, HARRY A. TAYLOR, a citizen of the United States, residing in the borough of Manhattan, city, county, and State of New York, have invented a new, original, and ornamental Design for Ladies' Undervests or Similar Undergarments, of which the following is a specification, reference being had to the accompanying drawings, forming part thereof.

Figure 1 is a view of a lady's undervest showing my new design; Figs. 2 and 3 are views much enlarged for the sake of more clear illustration, of the front and back respectively of that part only of the garment which is novel.

I claim:

The ornamental design for a lady's undervest or similar undergarment as shown.

HARRY A. TAYLOR.
